UNITED STATES PATENT OFFICE.

WILLIS C. WEBSTER, OF DUBOIS, PENNSYLVANIA, ASSIGNEE TO BUFFALO AIR-BRAKE COMPANY, OF PHOENIX, ARIZONA, A CORPORATION OF ARIZONA.

DOUBLE-HEADING VALVE.

1,255,253.

Specification of Letters Patent.

Patented Feb. 5, 1918.

Application filed May 28, 1915. Serial No. 31,029.

To all whom it may concern:

Be it known that I, WILLIS C. WEBSTER, a citizen of the United States, residing at Dubois, in the county of Clearfield and State 5 of Pennsylvania, have invented certain new and useful Improvements in Double-Heading Valves, of which the following is a specification.

My present invention relates to new and 10 useful improvements in air brake systems, the primary object of my invention consisting in the provision of a double heading valve by means of which, when two or more engines form part of the same train, the engineer of one of the engines, generally of the leading engine, may have control of all the 15 air pumps, main reservoirs and kindred mechanisms of the other engine equipments.

Heretofore, to the best of my knowledge, 20 each engine equipment has included a cut out cock which, upon all but the leading engine, is closed when double heading in order that the engineer of the leading engine may have complete control of the application 25 and release of the brakes. As a result, with the systems now in use, the air pumps, main reservoirs, etc., of all but the controlling engine are useless in double heading. Furthermore, it is impossible for the engineer 30 of any but the leading engine to either apply the brakes or give the engineer of the forward engine the benefit of his main reservoirs without first manually opening this cut out cock. Opening of this cut out cock is 35 prohibited upon practically all roads, due to the danger that the engineer, after opening it, will forget to close it and thereby prevent any application of the brakes by the engineer of any engine in the train, this being due to 40 the fact that as soon as any brake valve is so positioned as to feed air to the train line, it will be impossible for any engineer, by manipulating another brake valve to properly vent the train line and obtain application 45 of the brakes throughout the train.

Inasmuch as double heading is usually resorted to only upon extremely long trains or upon trains in exceptionally mountainous country where constant brake application is 50 required, it will be clear that either an exceptionally long train line must be built up, as in the former instance, or that only a very short time will be available in which to build

up the train line, as in mountainous service. It is therefore very difficult for the equipment of any one engine to properly operate and maintain the air brake system during double heading service and my present invention aims to overcome this difficulty by putting the locomotive equipments of all 60 following engines at the service of the engineer of the leading engine.

To accomplish this I provide, in connection with the usual cut out cock, what I term a double heading valve which is automatically controlled by changes in train line pressure and which includes a piston operated slide valve and graduating valve which, when the double heading valve is cut in, causes an automatic feed valve, constituting 70 a portion of my air brake system to feed air from the main reservoir to the train line at a rate solely dependent upon the relative pressures in the main reservoir and train line and the capacity of the passages forming the communication between them until the pressure in the train line has been brought up to normal pressure. It will be clear that inasmuch as this double heading valve is cut in and cut out automatically 80 upon a rise or a decrease in pressure in the train line, it will also be cut in and cut out by manipulation of a brake valve of any locomotive equipment to release and service positions. In this connection, a further object of my invention consists in so constructing the double heading valve and in so applying it in my air brake system that it will be cut in and out under proper circumstances, irrespective of whether it is located 90 upon the leading engine or following engine, that is, in such a manner that it will be cut in and out upon all suitable changes in train line pressure. By this means, the valve is kept in constant use, even upon locomotives 95 which may have their double heading cut out valve or cock closed for weeks at a time, thereby preventing possible sticking of the double heading valve, due to gumming and drying of oil about the piston controlling it. 100

A still further object of my invention consists in so arranging the double heading valve that in coupling additional cars to the train, the double heading valve will be automatically cut in to insure a proper building 105 up of the increased train line volume.

A still further object of my invention is to provide, in connection with the double heading valve, a double heading reservoir in order to provide a sufficient valve chamber 5 volume to insure proper controlling of the movement of the valve and to so arrange the valve that the pressure in the valve chamber proper and its reservoir will be reduced upon reduction of the train line in order that the 10 pressure therein will be maintained at train line pressure.

Another object of my present invention consists in arranging the double heading valve in such a manner that if the double 15 heading valve of a following engine cuts off before the train line is fully charged, the engineer of the first engine may cut it in again by merely moving his brake valve to lap position and then back to release position, this movement of the brake valve causing 20 a sudden fluctuation of air in the train line sufficient to cut in the double heading valve of the following engine.

My invention further comprehends the 25 provision of a double heading valve adapted to operate in connection with a brake valve when the latter is set in running service position and so arranged that the engineer in a following engine may apply the brakes upon 30 the train, irrespective of the engineer in the forward or controlling engine by moving his brake valve to quick service position. However, I arrange the double heading valve in such a manner that it will be impossible for 35 him to release the brakes by any ordinarily permitted manipulation of the brake valve, thereby preventing any likelihood of the engineer upon a following engine attempting to build up the train line when the engineer 40 upon the leading engine may be desirous of venting it to make a brake application.

One of the main objects of my invention is the provision of a double heading valve having an automatic cut out position.

45 A still further object of my invention consists in providing a novel means for holding the slide valve to its valve seat against main reservoir pressure even though there is no pressure in the valve chamber 50 itself.

And a still further object of my invention consists in providing means whereby the movement of the slide valve from release to service position, will be practically 55 instantaneous.

With these and other objects in view, my invention will be more fully described, illustrated in the accompanying drawings, and then specifically pointed out in the 60 claims which are attached to and form a part of this application.

In the drawings:

Figure 1 is a vertical, longitudinal sectional view of my improved double heading 65 valve;

Fig. 2 is a vertical, transverse sectional view taken on the line 2—2 of Fig. 1, looking in the direction of the piston;

Fig. 3 is a horizontal sectional view taken on the line 3—3 of Fig. 2;

Fig. 4 is a perspective view of the slide valve removed from the valve casing and stem of the piston;

Fig. 5 is a fragmentary sectional view, showing the slide valve seat in top plan;

Fig. 6 is a horizontal sectional view taken through the slide valve at a point slightly above the level of the slide valve seat, illustrating the slide valve in its automatic cut out position, which is its normal position, 80 the graduating valve and its seat being shown in dot and dash lines as such parts are located at an elevation above that at which the section is taken;

Fig. 7 is a diagrammatic view of the engine equipment of two connected engines, showing the position of the parts when the front engine has its brake valve set in release position;

Fig. 8 is a corresponding view, showing 90 the position of the parts when the brake valve of the leading engine is in service position, the brake valve of the following engine in both of the above figures being shown in running service position;

Fig. 9 is a diagrammatic view of the double heading valve in service lap position.

Corresponding and like parts are referred to in the following description and indicated in all the views of the drawings by the same reference characters.

In order to insure a clear, accurate and complete understanding of my improved double heading valve and its application 105 and employment in connection with my improved air brake system, I will first describe the mechanical structure of the valve itself and then explain, in connection with diagrammatic views of the engine equipments, its application and operation. Referring particularly to Figs. 1 to 6 of the drawings, it will be seen that my improved double heading valve includes a casing consisting of the main body member, indicated 110

as a whole by the numeral 10, the cap or bonnet members 11 and 12 closing the ends of the main body member and an upper body member 13 communicating with the intermediate portion of the main body 115 member. This main body member includes a cylindrical portion 14 provided throughout its extent with a cylindrical valve chamber 15, the lower wall of which is cut-away to provide a plane surfaced rectangular seat 120 16 for the slide valve, indicated as a whole by the numeral 17. At one end this intermediate body portion 10 is enlarged to form a cylindrical chamber 18 in which is reciprocally mounted a piston 19 having 125

a packing ring 20 closely engaging the peripheral wall of the chamber 18. This piston 19 has the usual stem 21 which extends axially of the chamber 15 and through a 5 spider 22 formed in the end bonnet 11, which bonnet is provided with a tapped bore 23. The bonnet 12 closes the outer end of the chamber 18 and is provided with a tapped bore 24. Gaskets 25 and 26 are 10 interposed between the ends of the intermediate body portion 10 of the valve casing and the bonnet portions 11 and 12 thereof in order to insure fluid tight joints.

As best shown in Fig. 1 of the drawings, 15 the piston stem 21 is provided with spaced annular shoulders 27 and 28 between which the slide valve seats, these shoulders being spaced from each other a distance somewhat greater than the length of the slide 20 valve in order to allow a certain amount of movement of the piston 19 independent of the slide valve. The slide valve 17, as clearly shown in Figs. 2 and 4 of the drawings, is formed throughout its length with 25 a channel 29 opening through its upper face and proportioned to snugly receive that portion of the piston stem 21 between the shoulders 27 and 28, said portion of the stem being squared for this purpose. At this 30 point, it should be noted that the walls 30, formed by this groove or channel, project somewhat above the upper face of the stem 21 when the slide valve rests evenly upon its valve seat 16.

The upper wall of the intermediate portion 10 of the valve casing is provided with a tapped opening to receive the threaded lower end of the cylindrical casing portion or member 13, this opening being directly 35 above the slide valve seat. A relatively heavy helical spring 31 fits snugly within the reduced intermediate portion 32 of the valve casing member 13 and the guide stem 33 of a pressure carriage 34 seats snugly 40 within the lower end of the spring 31, the carriage being located in the lower end of the portion 13 of the casing and including spaced side walls 35 provided in their lower ends with half bearings 36 to receive the 45 trunnions 37 of a roller 38. This roller is reduced in diameter at its ends in such a manner that its end portions may bear upon the upper edges of the walls 30 of the slide valve at the same time that its central portion 50 engages the upper face of the piston stem 21 in order that the roller may not hold the slide valve to its seat, but also hold the piston stem in place within the channel 29 of the slide valve. As a further result of this 55 arrangement, the walls 30 of the slide valve also hold the pressure carriage 34 against turning movement. An adjusting nut 39 is threaded into the upper or outer end of the portion 13 of the valve casing to engage 60 against the free end of the spring 31 and

properly tension it and, when adjusted, is held by a lock nut 40. The upper end of the portion 13 of the valve casing is closed by a plug 41 having a peripheral flange 42 which engages against a gasket 43 positioned against the end of the casing portion 13 in order to form an air tight closure for the valve casing. It will of course be understood that the spring 31 is so adjusted as to withstand all pressure which may be exerted against the lower face of the valve in any position which it may occupy and under all possible circumstances.

Reference to Fig. 5 of the drawings will show that the valve seat is provided along one side with spaced ports 44 and 45 and along its opposite side with spaced ports 46 and 47, the port 44 being of smaller diameter than the ports 45, 46 and 47 which are generally of substantially equal diameter. It will further be noted that the ports 46 and 47 are located nearer the piston chamber than the ports 44 and 45, respectively, the port 45 in effect being intermediate between the ports 46 and 47, while the port 46 is in turn intermediate between the ports 44 and 45. Passages 48, 49, 50 and 51 lead from the ports 44, 45, 46 and 47, respectively, to the atmosphere and the valve casing, about the outer ends of the passages 49, 50 and 51, 95 is counterbored to provide threaded sockets for the ends of certain pipes, the connections of which will be later explained.

Formed in the lower face of the slide valve 17, adjacent its forward end, namely, that end nearer the piston 19, is an angular cavity 52, one arm of which extends parallel to one side of the slide valve in position to communicate with the port 45 and the other arm of which extends diagonally toward the forward end of the slide valve in position to communicate with the port 47, this cavity being so proportioned that when the piston is in its innermost position and the slide valve consequently in its innermost position, the cavity will establish communication between the ports 45 and 47. That end of the cavity 52 which, in a certain position of the slide valve, communicates with the port 45, is formed with a reduced extension 53 through which such communication will be maintained during a considerable portion of the forward movement of the slide valve, while the lower face of the slide valve, at its outermost or forward end, is provided with a feed groove or channel 54 communicating at one end with the cavity 52 and opening at its other end through the forward end face of the slide valve, that is, behind the piston 19. An elongated cavity 55 is also formed in the lower face of the slide valve, parallel with its side face and adapted, in the extreme forward position of the piston and slide valve, to establish communication between the ports 46 and 47. This cavity 55,

at its forward end, is provided with a reduced extension 56 serving to maintain communication between the ports 46 and 47 for a considerable part of the rearward movement of the slide valve, this extension 56 being so related to the extension 53 that in a certain position of the slide valve, as shown in Fig. 6 of the drawings, the extensions 56 and 53 will both communicate with the ports 10 47 and 45, respectively.

In addition to the above described cavities formed in the lower face of the slide valve, the slide valve is provided with a longitudinally extending, preferably axially 15 formed cylindrical bore 57 opening through the forward end of the slide valve and terminating short of the opposite end of the slide valve in a frusto-conical valve seat 58 from which a passage 59 leads rearwardly 20 and downwardly through the lower face of the valve at such a point as to communicate with the port 44 when the slide valve and piston are at the extreme forward limit of their movement. A passage 60 opens into 25 the bore 57 of the slide valve immediately adjacent the valve seat 58 and communication between this passage 60 and the passage 59 is controlled by a cylindrical graduating valve 61 reciprocally mounted in the bore 57 30 and having a frusto-conical terminal for engagement with the seat 58. A pin 62, extending through a slot 63 formed in the upper wall of the slide valve, secures the graduating valve to the piston stem 21 in 35 such a manner that the two at all times move in unison.

At this point, and before in any way taking up the operation of my improved double heading valve, I wish to call attention to 40 the fact that that end of the chamber 15 communicating with the chamber 18 is surrounded by a peripheral flange 64 projecting a slight distance into the chamber 18 and forming a seat for the piston 19 when 45 the latter is at the extreme limit of its rearward movement whereby, under such circumstances, any pressure in the chamber 15 is exerted only upon a small area of the piston 19, while pressure in the chamber 18 is 50 directed against the entire outer face of the piston. It will of course be clear that as soon as the piston moves forwardly out of engagement with the annular seat 64, its entire rear surface will be subjected to whatever 55 pressure may be in the chamber 15, which constitutes the slide valve chamber.

In order to understand the operation of the above described cut off valve, a general understanding of the air brake system with 60 which it is employed, which system includes feed valves of a novel type, is necessary. These feed valves, together with an engineer's valve, form the subject matter of a separate application filed by me May 28, 65 1914, and bearing the Serial No. 841,657

and for this reason need not be here described in detail. Referring to Figs. 7 and 8 of the drawings, in which my improved engine equipment is illustrated diagrammatically, 65 indicates the main reservoir, 70 A a manually adjustable feed valve, B an automatic feed valve, C the brake valve and D my improved double heading valve. Air from the main reservoir passes through a pipe 66 to the hand controlled feed valve 75 and from this valve through a pipe 67 to the chamber above the rotary valve of the brake valve C, a pipe 68 leading from the brake valve to the train line E. A pipe 69 leads from the pipe 67 to the automatic feed 80 valve B and a pipe 70 leads from this feed valve to the brake valve in order that the train line pressure may be maintained by air fed from the automatic feed valve B when the brake valve is in running service 85 position, as particularly pointed out and explained in the above referred to application. The feeding of air from the main reservoir to the chamber above the rotary valve of the brake valve, through the man- 90 ually adjustable feed valve A is, aside from the adjustment of such valve, dependent upon the pressure in the chamber 71 of the feed valve A, a pipe 72 establishing communication between this chamber and the 95 pipe 68 which communicates with the train line. This pipe 72 is formed intermediate its length with a reduced passage 73 in order that fluctuations of pressure in the train line may not be too rapidly transmitted to the chamber 71 and the feed valve A, when operating independently of the feed valve B, supplies air to the brake valve 100 at standard train line pressure. A pipe 74 leads from an equalizing reservoir 75 to 105 a controlling chamber 76 of the automatic feed valve B and in running service position of the brake valve, air is fed from the automatic feed valve B through the brake valve to the train line by way of the pipe 110 70 to maintain the train line at the same pressure as that in the equalizing reservoir, that is, at the same pressure as that in the controlling chamber 76. Further description of the manually adjustable feed valve 115 A and automatic feed valve B is believed to be unnecessary in view of the fact that they form no part of the present invention. At the same time, attention is directed to the fact that the manually adjustable feed valve A is adapted to feed air from the main reservoir at standard train line pressure when the brake valve is in release position and is adapted to feed air to the automatic feed valve at main reservoir pressure when 120 the brake valve is in running service position, the direct communication through the pipe 67 to the brake valve being lapped at the brake valve in such position. Pipes 77 and 78 lead from the pipe 66 to a pump 130

governor, not shown, and a pipe 79 also leads from the pipe 67 to the pump governor. A pipe 80 also leads from the pipe 74 to chamber D of the brake valve in order that the pressure in the controlling chamber 76 of the feed valve B, in the equalizing reservoir and in chamber D may, at all times, be the same. The above described connections are the same as in my application on brake valves, previously referred to.

In addition to these connections, a pipe 81 leads from the pipe 80 and, consequently, from the controlling chamber 76 of the automatic feed valve B to the passage 51 of my double heading valve D. Furthermore, a pipe 82 leads from the pipe 66 and, consequently, from the main reservoir to the passage 49 of my double heading valve, and a pipe 83 leads from the train line to the passage 50 of the double heading valve. A pipe 84 leads from the train line to the chamber 18 of the double heading valve, being threaded into the bonnet 12, and a pipe 85, threaded into the bonnet 11, leads from the valve chamber of my double heading valve to what I term a double heading valve reservoir 86. A manually operable cut off valve 87, of any suitable type, is interposed in the pipe 81 in order that the double heading valve D may be rendered operative or inoperative at the will of the engineer.

It should be noted that in Figs. 7 and 8 of the drawings I have illustrated two engine equipments operating in conjunction with each other, the equipment at the right, in each instance, being that of the forward engine and that at the left that of a second following engine, these figures clearly illustrating the operation of my double heading valve in use. It will further be noted that in double heading, the cut off valve or cock 87 of the rear engine is opened and the brake valve of such engine set in running service position in order that, under proper circumstances, air may be fed to the train line from the main reservoir through the automatic feed valve B of the second engine. It will of course be understood that if a third or even a fourth engine was in use, the brake valve of such engine would be turned to running service position and its cut off valve also opened.

In Fig. 6 I have illustrated the automatic cut out position of my double heading valve, which is the normal position of the valve when the train is running without application of the brakes. In this position, the slide valve and piston are substantially midway of their movement and the graduating valve is open. There is communication between the chamber 76 of the automatic feed valve B and the train line through the pipe 81, passage 51, port 47, cavity 55 of the slide

valve, port 46, passage 50 and pipe 83. There is also, as a rule, a slight feeding of air from the main reservoir through the pipes 66 and 82 to the passage 49, port 45, cavity 52 and its feed passage 54 to the chamber 15 of the double heading valve. The purpose of this feeding, however, is merely to keep the pressure in the chamber 15 of the double heading valve equal to the train line pressure in the chamber 18 of the valve in order to prevent any movement of the piston and, consequently, of the slide valve and its graduating valve. If there is no leakage from the chamber 15 or from the double heading valve reservoir 86, the building up of pressure from the main reservoir to the chamber 15 will cause a slight forward movement of the piston and slide valve to cut off communication between the port 45 and cavity 52 and, therefore, prevent feeding of air from the main reservoir to the chamber 15.

In describing the operation of my double heading valve, I will assume that it is in its automatic cut out position, as shown in Fig. 6, and that a train line reduction is made in the usual manner by moving the brake valve of the leading engine to service position and then back to running service position, described in my above referred to brake valve application. Under these conditions, the brake valve of the leading engine will operate, in conjunction with the automatic feed valve of such engine, to feed air to the train line to maintain it at whatever pressure to which it has been reduced. If the train is exceptionally long, or if the train line is leaky, it will be clear that the feeding of air from the main reservoir of the leading engine will, if just sufficient to properly maintain this train line pressure, be insufficient to later build it up and also maintain it and this is one of the reasons for the provisions of my double heading valve. The double heading valves of both engines operate simultaneously and in the same manner, under all conditions, but the action of the double heading valve upon the leading or controlling engine has no effect upon the operation of the air brake system and need not in any way be considered, the only advantage in having it operate at all times being that such operation tends to prevent sticking of the piston and slide valve, due to gumming and drying of oil or dirt in the double heading valve and, therefore, tends to keep the valve in proper working order.

Considering the operation of my improved double heading valve, reference being particularly had to the valve upon the second or following engine, it will be clear that, as soon as the train line pressure is reduced, the pressure in the chamber 18 will fall below that in the chamber 15, with the result that the piston 19 will move to its ex-

treme forward position, moving the slide valve and graduating valve with it, the parts coming to the position shown at the left in Fig. 8. At this time, inasmuch as the 5 brake valve upon the following engine is in running service position, the communication between the controlling chamber 76 and brake valve is cut off. However, this controlling chamber 76 and the equalizing reservoir 75 are, in the forward position of the slide valve of the double heading valve, in direct communication with the train line through the pipe 81, port 47, cavity 55, port 46 and pipe 83 and these pressures will, 10 therefore, be reduced to the same pressure as the train line which has been reduced by manipulation of the brake valve of the forward engine. Furthermore, this movement of the slide valve of my double heading 15 valve to its forward position brings the port 59 into registration with the port 44 of the valve seat and air is, therefore, vented from the double heading valve reservoir 86 and from the valve chamber 15 to the atmosphere, 20 thereby reducing the pressure against the rear face of the piston 19. It will be clear that as soon as this pressure is reduced slightly below the pressure in the chamber 18, that is, the train line pressure, 25 the piston 19 will move rearwardly. Under these circumstances, the graduating valve 61, which is connected to the stem 21 of the piston, is moved to closed position to cut off further escape of air from the valve chamber 15 to the atmosphere. This cutting off 30 of air, of course, prevents further decrease of pressure in the chamber 15, with the result that no further movement of the piston 19 takes place and the double heading valve 35 is then in its service lap position, illustrated diagrammatically in Fig. 9 of the drawings. As will be seen by reference to this figure, both the ports 44 and 45 are lapped, while direct communication between the 40 controlling chamber 76 of the automatic feed valve B and the train line is established from the port 47 through the cavity 55 to the port 46. The controlling chamber 76 of the automatic feed valve of the second 45 engine is, therefore, subjected only to train line pressure and this pressure, will not cause it to feed any air to the train line, the reduced pressure in the train line being maintained solely by the automatic feed valve of the forward engine, the controlling chamber of which is subject to the reduced equalizing reservoir pressure.

It will therefore be seen that during a 50 service application of the brakes, the double heading valve is in effect cut out, although occupying a different position from the automatic cut out position shown in Fig. 6 of the drawings.

When the brake valve upon the leading 55 engine is turned to release position to build

up the train line and release the brakes, air entering the train line from the leading engine builds up the pressure in the chamber 18 of the double heading valves of both engines, causing their pistons to move inwardly to their full extent. Under these conditions, the slide valves and graduating valves occupy the position illustrated in Fig. 7. Referring more particularly to the double heading valve upon the second engine, 70 it will be seen that while the port 46 still communicates with the cavity 55, this cavity no longer communicates with the port 47, and there is no communication between the train line and the pipe 81. On the other hand, the cavity 52 of the slide valve establishes direct communication between the ports 45 and 47 and air, therefore, flows directly from the main reservoir through the pipe 66 and 82, the passage 49, cavity 52, 75 passage 51 and pipe 81 to the controlling chamber 76 of the automatic feed valve, pressure in this chamber being therefore maintained at the same degree as the main reservoir pressure and the automatic feed valve B being therefore held against closing movement. Under these circumstances, air will be fed from the main reservoir, through the feed valve B, pipe 70, brake valve and pipe 68, all on the second engine, 80 to the train line E to assist the equipment of the first engine in building up the train line to the proper pressure. At the same time that this is happening, air is slowly escaping from the cavity 52 through the feed groove 54 into the chamber 15 behind the piston 19 and of course through the pipe 85 to the double heading valve reservoir 86. As soon as this pressure in the chamber 15 85 becomes somewhat greater than that in the chamber 18, the piston will again move outwardly until communication between the ports 45 and 47 through the cavity 52, is cut off or nearly cut off, at which time the cavity 55 will begin to establish communication between the ports 46 and 47, it will therefore be clear that as soon as feed of main reservoir air to the controlling chamber 76 of the feed valve B is cut off, such chamber is placed in communication with the train line and therefore vented into the train line until its pressure is the same as that of the train line. Under these conditions, it will of course be clear that the feed valve B can no longer supply air to the train 90 line. If there is no leakage in the double heading valve or its reservoir, the communication between the port 45 and cavity 52 will be completely cut off, while if there is a slight leakage, the reduced extension 53 of the cavity 52 will still continue to register with the port 45 to maintain the pressure in the chamber 15 and reservoir 85 at the same 95 pressure as that in the train line.

It will therefore be seen that by providing 100

my improved double heading valve, I give the engineer of the leading engine full control of the air pumps, main reservoirs and kindred mechanisms of the equipments of 5 any other engines in the train. This increase in air volume permits a more rapid building up of train line pressure and, consequently, a more rapid release of the brakes. Furthermore, because of this increased 10 volume, it is comparatively easy to maintain the desired pressure in the main reservoirs, under all conditions.

Although the double heading valve is automatic in its action, it may be cut in and 15 out, at any time, by proper manipulation of the brake valve. For instance, if on a long train, the double heading valve of the rear engine cuts out before the train line is fully charged, the engineer of the forward engine 20 may cut it in again by moving his brake valve to lap position and then back to release position, thereby causing a sudden fluctuation of air in the train line which is sufficient to move the piston of the double heading valve. At this point, it should be 25 noted that even though the train line should be fully charged at the time the engineer of the forward engine cuts the double heading valve in, no over-charging of the train 30 line would occur as the manually adjustable feed valve A would, under these circumstances, prevent feeding of air from the main reservoir of the second engine to the train line, even though the controlling chamber 35 of the automatic feed valve B was subject to main reservoir pressure. The same will be true if the volume of air in the main reservoirs is as great or greater than the volume of the train line, as the train line 40 will then be charged before the double heading valve would act and the automatic feed valve would still be subject to main reservoir pressure. The train line pressure, however, will cause the hand controlled feed 45 valve to cut off the flow of air from the main reservoir to the automatic feed valve and the double heading valve will soon be forced over to establish communication between the controlling chamber of the automatic feed valve and train line to reduce 50 the pressure in such controlling chamber to that in the train line.

It should be noted that after release, the 55 double heading valve automatically returns to its normal or automatic cut out position and therefore establishes communication between the controlling chamber of the automatic feed valve and the train line so that any further reduction of train line pressure, 60 even though slight, causes a corresponding reduction of pressure in the controlling chamber of the automatic feed valve and so prevents feeding of air to the train line.

The manually adjustable or hand controlled feed valve A of the second engine is

ordinarily set for a little lower pressure than that of the front engine in order that, if the train line builds up quickly and a second application is immediately required, the engineer on the forward engine may, by 70 a very slight reduction, cut out the double heading valve of the other engine and prevent feed of air to the train line by the second engine, even though there is main reservoir pressure in the controlling chamber of the automatic feed valve as the hand controlled feed valve will be shut. As a heavy reduction is necessary at this time, to apply the brakes, due to the train line pressure being above the auxiliary reservoir 80 pressure, the double heading valve of the rear engine cannot help but be cut out.

Having thus described the invention, what is claimed as new is:

1. In a fluid pressure brake system, the 85 combination with a plurality of locomotive equipments coöperating with a common train line and each including a main reservoir, a brake valve adapted in running service and release positions to feed fluid to the 90 train line, and a valve having a pressure chamber controlling feed of fluid to the brake valve and train line in running service position of the brake valve and at the reduced train line pressure to maintain such 95 pressure, of means in each equipment operable when the brake valve of such equipment is in running service position and upon movement of the brake valve of another equipment to release position to cause 100 the feed and brake valves of the equipment, the brake valve of which is in running service position, to feed fluid to the train line at a rate solely dependent upon the relative pressures in the main reservoir and train 105 line and the capacity of the passages forming the communication between them.

2. In a fluid pressure brake system, the 110 combination with a plurality of locomotive equipments coöperating with a common train line and each including a main reservoir, a brake valve adapted, in running service and release positions, to feed fluid to the train line and a feed valve having a pressure chamber normally subject to train 115 line pressure and vented in proportion to the venting of the train line, said pressure chamber controlling feed of fluid to the brake valve and train line in running service position of the brake valve 120 and at the reduced train line pressure to maintain such pressure, of means in each equipment operable when the brake valve of such equipment is in running service position and upon movement of the brake 125 valve of another equipment to release position to cause the feed and brake valves of the equipment, the brake valve of which is in running service position, to feed fluid to the train line at a rate solely dependent 130

upon the relative pressures in the main reservoir and train line and the capacity of the passages forming the communication between them.

- 5 3. In a fluid pressure brake system, the combination with a plurality of locomotive equipments coöperating with a common train line and each including a main reservoir, a brake valve adapted, in running service and release positions, to feed fluid to the train line and a feed valve having a pressure chamber normally subject to train line pressure and vented in proportion to the venting of the train line, said pressure chamber controlling feed of fluid to the brake valve and train line in running service position of the brake valve and at the reduced train line pressure to maintain such pressure, of means operable upon a slight 10 increase in train line pressure to establish communication between the main reservoir and pressure chamber of the feed valve.
4. In a fluid pressure brake system, the combination with a plurality of locomotive equipments coöperating with a common train line and each including a main reservoir, a brake valve adapted, in running service and release positions, to feed fluid to the train line and a feed valve having a pressure chamber vented in proportion to the venting of the train line, said pressure chamber controlling feed of fluid to the brake valve and train line in running service position of the brake valve and at the reduced 15 train line pressure to maintain such pressure, of means capable of being cut in to establish communication between the train line and the pressure chamber of the feed valve.
5. In a fluid pressure brake system, the combination with a plurality of locomotive equipments coöperating with a common train line and each including a main reservoir, a brake valve adapted, in running service and release positions, to feed fluid to the train line and a feed valve having a pressure chamber vented in proportion to the venting of the train line, said pressure chamber controlling feed of fluid to the brake 20 valve and train line in running service position of the brake valve and at the reduced train line pressure to maintain such pressure, of means capable of being cut in to establish communication between the train line and the pressure chamber of the feed valve.
6. In a fluid pressure brake system, the combination with a main reservoir, a train line, a brake valve and a feed valve adapted to normally feed air to the brake valve and so to the train line in running service position of the brake valve to maintain the re-

duced train line pressure, of means capable of being cut in to render such feed valve inoperative upon sudden lowering of pressure in the train line and to cause it to feed air to the train line at a rate solely dependent upon the relative pressures in the main reservoir and train line and the capacity of the passages forming the communication between them upon increase in train line pressure.

7. In fluid pressure brake systems, a train line, a plurality of locomotive equipments coöperating with the train line and each including a main reservoir, an engineer's valve, a feed valve controlling passage of fluid from the main reservoir to the engineer's valve and so to the train line during release position of the engineer's valve, a feed valve controlling the passage of fluid from the main reservoir to the engineer's valve and so to the train line in the running service position of the engineer's valve, and means whereby a reduction in train line pressure caused by movement of one engineer's valve will automatically cut out the feed valves of the remaining locomotive equipments.

8. In fluid pressure brake systems, a train line, a plurality of locomotive equipments coöperating with the train line and each including a main reservoir, an engineer's valve, a feed valve controlling passage of fluid from the main reservoir to the engineer's valve and so to the train line during release position of the engineer's valve, a feed valve controlling the passage of fluid from the main reservoir to the engineer's valve and so to the train line in the running service position of the engineer's valve, and means whereby an increase of pressure in the train line through the operation of one of the engineer's valves will automatically cut in the feed valves of the other locomotive equipments.

9. In fluid pressure brake systems, a train line, a plurality of locomotive equipments coöperating with the train line and each including a main reservoir, an engineer's valve, a feed valve controlling passage of fluid from the main reservoir to the train line during release position of the engineer's valve, a feed valve controlling the passage of fluid from the main reservoir to the train line in the running service position of the engineer's valve, and means whereby an increase of pressure in the train line through the operation of one of the engineer's valves will automatically cut in the feed valves of the other locomotive equipments, said means feeding air to the train line at substantially main reservoir pressure.

10. In fluid pressure brake systems, a train line, a plurality of locomotive equipments coöperating with the train line and each including a main reservoir, an engi-

neer's valve, a feed valve controlling passage of fluid from the main reservoir to the engineer's valve and so to the train line during release position of the engineer's valve,

- 5 a feed valve controlling the passage of fluid from the main reservoir to the train line in the running service position of the engineer's valve, and means whereby a reduction in train line pressure caused by movement 70
10 of one engineer's valve will automatically cut out the feed valves of the remaining locomotive equipments and whereby an increase of pressure in the train line through operation of the engineer's valve will automatically cut in the feed valves of the other 75
15 locomotive equipments.

11. In fluid pressure brake systems, the combination with a plurality of locomotive equipments each including a main reservoir, 20 a brake valve and feed valves, and a train line common to all equipments, of means whereby the feed valve of any brake valve in running service position will, upon movement of another brake valve to release position feed fluid to the train line at a rate 80
25 solely dependent upon the relative pressures in the main reservoir and train line and the capacity of the passages forming the communication between them.

30 12. In fluid pressure brake systems, the combination with a plurality of locomotive equipments each including a main reservoir, a brake valve and feed valves, and a train line common to all equipments, of means 85
35 whereby the feed valve of any brake valve in running service position will, upon movement of another brake valve to release position, feed fluid to the train line at a rate 90
40 solely dependent upon the relative pressures in the main reservoir and train line and the capacity of the passages forming the communication between them and cut off such 95
45 feed when the train line has been charged to normal pressure.

45 13. In fluid pressure brake systems, the combination with a train line and a plurality of locomotive equipments, each coöperating 100
50 with the train line and each including a main reservoir, a brake valve and feed valves, of means operable upon one locomotive 105
55 equipment to give another locomotive equipment control of the former's feed valves, main reservoir and brake valve, said means permitting the subservient equipment to charge the train line at a rate solely 110
60 dependent upon the relative pressures in the main reservoir and train line and the capacity of the passages forming the communication between them when the brake valve 115
65 of the controlling equipment is turned to release position.

14. In fluid pressure brake systems, the combination with a train line and a plurality of locomotive equipments, each coöperating 120
65 with the train line and each including a

main reservoir, a brake valve and feed valves, of means operable upon one locomotive equipment to give another locomotive equipment control of the former's feed valves, main reservoir and brake valve, said 70
means preventing the subservient equipment feeding air to the train line when the brake valve of the controlling equipment is in service position and causing the subservient equipment to feed air to the train line at a 75
rate solely dependent upon the relative pressures in the main reservoir and train line and the capacity of the passages forming the communication between them when the 80
brake valve of the controlling equipment is 85
in release position.

15. In fluid pressure brake systems, the combination with a train line and a plurality of locomotive equipments, each coöperating 90
95 with the train line and each including a main reservoir, a brake valve and feed valves, of means operable upon one locomotive equipment to give another locomotive equipment control of the former's feed valves, main reservoir and brake valve, said 100
means preventing the subservient equipment feeding air to the train line when the brake valve of the controlling equipment is in service position and causing the subservient equipment to feed air to the train line at a 105
rate solely dependent upon the relative pressures in the main reservoir and train line and the capacity of the passages forming the communication between them when the 110
brake valve of the controlling equipment is 115
in release position, and being such that the feeding of air to the train line is automatically stopped when the train line pressure becomes normal.

16. In a fluid pressure brake system, the combination with a train line and a plurality of locomotive equipments coöperating 120
110 with the train line, of a double heading valve co-acting with each equipment and each, when active, rendering its equipment 115
subservient to an equipment, the double heading valve of which is inactive, the double heading valves being automatic in their action and operating whether active or inactive but without effect when inactive.

17. In fluid pressure brake systems, the combination with a train line, a brake valve adapted, in running service position, to feed fluid to the train line, a feed valve controlling feed of fluid to the brake valve, a main reservoir, and a second feed valve controlling feed of fluid from the main reservoir to the first feed valve, of a train line pressure governed double heading valve controlling 125
the first feed valve.

18. In fluid pressure brake systems, the combination with a train line, a brake valve adapted, in running service position, to feed fluid to the train line, a feed valve controlling feed of fluid to the brake valve, a main 130
125

reservoir, and a second feed valve controlling feed of fluid from the main reservoir to the first feed valve, of train line pressure governed means controlling the first feed valve, and means for cutting said latter controlling means in and out.

19. In fluid pressure brake systems, the combination with a train line, a brake valve adapted, in running service position, to feed fluid to the train line, a feed valve controlling feed of fluid to the brake valve, a main reservoir, and a second feed valve controlling feed of fluid from the main reservoir to the first feed valve, of train line pressure governed means controlling the first feed valve, said latter controlling means, upon increase of pressure in the train line, causing the first feed valve to supply air to the brake valve and so to the train line to build up the train line pressure.

20. In fluid pressure brake systems, the combination with a train line, a brake valve adapted, in running service position, to feed fluid to the train line, a feed valve controlling feed of fluid to the brake valve, a main reservoir, and a second feed valve controlling feed of fluid from the main reservoir to the first feed valve, of train line pressure governed means controlling the first feed valve, said latter controlling means, upon a quick decrease in train line pressure, rendering the first feed valve inactive and cutting off flow of fluid to the train line.

21. In fluid pressure brake systems, the combination with a train line, a brake valve adapted, in running service position, to feed fluid to the train line, a feed valve controlling feed of fluid to the brake valve, a main reservoir, and a second feed valve controlling feed of fluid from the main reservoir to the first feed valve, of train line pressure governed means controlling the first feed valve, said latter controlling means, upon a quick increase in train line pressure, causing the first feed valve to feed fluid to the train line at a rate solely dependent upon the relative pressures in the main reservoir and train line and the capacity of the passages forming the communication between them.

22. In fluid pressure brake systems, the combination with a train line, a brake valve adapted, in running service position, to feed fluid to the train line, a feed valve controlling feed of fluid to the brake valve, a main reservoir, and a second feed valve controlling feed of fluid from the main reservoir to the first feed valve, of train line pressure governed means controlling the first feed valve, said latter controlling means, upon a quick increase in train line pressure, causing the first feed valve to feed fluid to the train line at a rate solely dependent upon the relative pressures in the main reservoir and train line and the capacity of the passages forming the communica-

cation between them, while the second feed valve automatically cuts off feed of fluid to the train line when the pressure therein reaches normal.

23. In fluid pressure brake systems, the combination with a train line, a brake valve adapted, in running service position, to feed fluid to the train line, a feed valve controlling feed of fluid to the brake valve, a main reservoir, and a second feed valve controlling feed of fluid from the main reservoir to the first feed valve, of train line pressure governed means controlling the first feed valve, said latter controlling means, upon a rapid decrease in train line pressure, cutting off feed of air between the first feed valve and brake valve and upon a rapid rise in pressure causing the first feed valve to feed air to the brake valve at a rate solely dependent upon the relative pressures in the main reservoir and train line and the capacity of the passages forming the communication between them.

24. In fluid pressure brake systems, the combination with a train line, a brake valve adapted, in running service position, to feed fluid to the train line, a feed valve having a pressure chamber controlling feed of fluid to the brake valve, a main reservoir, and a second feed valve having a pressure chamber communicating with the train line and controlling feed of fluid from the main reservoir to the first feed valve, of a double heading valve controlled by train line pressure and when cut in controlling one of the feed valves.

25. In fluid pressure brake systems, the combination with a train line, a brake valve adapted, in running service position, to feed fluid to the train line, a feed valve having a pressure chamber controlling feed of fluid to the brake valve, a main reservoir, and a second feed valve having a pressure chamber communicating with the train line and controlling feed of fluid from the main reservoir to the first feed valve, of a double heading valve controlled by train line pressure and when cut in controlling one of the feed valves, and manually operable means for rendering the double heading valve active and inactive.

26. In fluid pressure brake systems, the combination with a train line, a brake valve adapted, in running service position, to feed fluid to the train line, a feed valve having a pressure chamber controlling feed of fluid to the brake valve, a main reservoir, and a second feed valve having a pressure chamber communicating with the train line and controlling feed of fluid from the main reservoir to the first feed valve, of a double heading valve controlled by train line pressure, said double heading valve, upon a slight decrease in train line pressure, for establishing and maintaining or if estab-

lished for maintaining communication between the pressure chamber of the first valve and the train line.

27. In fluid pressure brake systems, the combination with a train line, a brake valve adapted, in running service position, to feed fluid to the train line, a feed valve having a pressure chamber controlling feed of fluid to the brake valve, a main reservoir, and a second feed valve having a pressure chamber communicating with the train line and controlling feed of fluid from the main reservoir to the first feed valve, of a double heading valve controlled by train line pressure, said double heading valve, upon a rapid decrease in train line pressure, for establishing and maintaining or if established for maintaining communication between the pressure chamber of the first feed valve and the train line.

28. In fluid pressure brake systems, the combination with a train line, a brake valve adapted, in running service position, to feed fluid to the train line, a feed valve having a pressure chamber controlling feed of fluid to the brake valve, a main reservoir, and a second feed valve having a pressure chamber communicating with the train line and controlling feed of fluid from the main reservoir to the first feed valve, of a double heading valve controlled by train line pressure, said double heading valve, upon a quick rise in train line pressure, establishing communication between the pressure chamber of the first feed valve and the main reservoir.

29. In fluid pressure brake systems, the combination with a train line, a brake valve adapted, in running service position to feed fluid to the train line, a feed valve having a pressure chamber controlling feed of fluid to the brake valve, a main reservoir, and a second feed valve having a pressure chamber communicating with the train line and controlling feed of fluid from the main reservoir to the first feed valve, of a double heading valve controlled by train line pressure, said double heading valve, upon a quick rise in train line pressure, establishing communication between the pressure chamber of the first feed valve and the main reservoir and upon a decrease in train line pressure establishing and maintaining or if established maintaining communication between the same pressure chamber and the train line.

30. In fluid pressure brake systems, the combination with a train line, a brake valve adapted, in running service position, to feed fluid to the train line, a feed valve having a controlling chamber governing the feed of fluid to the brake valve, a main reservoir, and a second feed valve having a controlling chamber subject, at all times, to train line pressure and governing the feed of fluid

from the main reservoir to the first feed valve, of a double heading valve controlling communication between the pressure chamber of the first feed valve and the train line and between the pressure chamber of the first feed valve and the main reservoir, and means for cutting off communication between such pressure chamber and the double heading valve.

31. In fluid pressure brake systems, the combination with a train line, a brake valve adapted, in running service position, to feed fluid to the train line, a feed valve having a controlling chamber governing the feed of fluid to the brake valve, a main reservoir, and a second feed valve having a controlling chamber subject, at all times, to train line pressure and governing the feed of fluid from the main reservoir to the first feed valve, of a double heading valve controlling communication between the pressure chamber of the first feed valve and the train line and between the pressure chamber of the first feed valve and the main reservoir.

32. In a fluid pressure brake system, the combination with a train line, a brake valve adapted, in running service position, to feed fluid to the train line, a pressure chamber governed feed valve controlling feed of fluid to the brake valve in such position, a main reservoir, and a second pressure chamber governed feed valve controlling feed of fluid from the main reservoir to the first feed valve, of a double heading valve capable of controlling one of the feed valves and including a valve proper, a pressure chamber, and a piston dividing the pressure chamber and controlling the valve, being subjected, upon one side, to actual train line pressure at all times and normally subjected, upon its other side, to standard train line pressure.

33. In a fluid pressure brake system, the combination with a train line, a brake valve adapted, in running service position, to feed fluid to the train line, a pressure chamber governed feed valve controlling feed of fluid to the brake valve in such position, a main reservoir, and a second pressure chamber governed feed valve controlling feed of fluid from the main reservoir to the first feed valve, of a double heading valve capable of controlling one of the feed valves and including a valve proper, a pressure chamber, and a piston dividing the pressure chamber and controlling the valve, being subjected, upon one side, to actual train line pressure at all times and normally subjected, upon its other side, to standard train line pressure, the movement of the piston, upon venting of train line pressure, causing the valve to correspondingly vent that side of the chamber normally subjected to normal train line pressure.

34. In a fluid pressure brake system, the combination with a train line, a brake valve adapted, in running service position, to feed fluid to the train line, a pressure chamber governed feed valve controlling feed of fluid to the brake valve in such position, a main reservoir, and a second pressure chamber governed feed valve controlling feed of fluid from the main reservoir to the first feed valve, of a double heading valve capable of controlling the first feed valve and including a valve proper, a pressure chamber, and a piston dividing the pressure chamber and controlling the valve, being subjected, upon one side, to actual train line pressure at all times and normally subjected, upon its other side, to standard train line pressure, the movement of the piston, upon venting of train line pressure, causing the valve to correspondingly vent that side of the chamber normally subjected to normal train line pressure, and means carried by the valve proper and controlled by the piston for cutting off venting of such side of the chamber upon cutting off venting of the train line.

35. In a fluid pressure brake system, the combination with a train line, a brake valve adapted, in running service position, to feed fluid to the train line, a pressure chamber governed feed valve controlling feed of fluid to the brake valve in such position, a main reservoir, and a second pressure chamber governed feed valve controlling feed of fluid from the main reservoir to the first feed valve, of a double heading valve including a valve proper, a pressure chamber, and a piston dividing the pressure chamber and controlling the valve, being subjected, upon one side, to actual train line pressure at all times and normally subjected, upon its other side, to standard train line pressure, movement of the piston, due to a sudden rise in train line pressure, causing the valve to establish communication between the main reservoir and the pressure chamber of the first feed valve.

36. In a fluid pressure brake system, the combination with a train line, a brake valve adapted, in running service position, to feed fluid to the train line, a pressure chamber governed feed valve controlling feed of fluid to the brake valve in such position, a main reservoir, and a second pressure chamber governed feed valve controlling feed of fluid from the main reservoir to the first feed valve, of a double heading valve including a valve proper, a pressure chamber, and a piston dividing the pressure chamber and controlling the valve, being subjected, upon one side, to actual train line pressure at all times and normally subjected, upon its other side, to standard train line pressure, movement of the piston, due to a sudden rise in train line pressure, causing the valve to establish communication between the main

reservoir and the pressure chamber of the first feed valve and also causing it to establish a relatively slight communication between the main reservoir and that side of the piston normally subject to standard train line pressure.

37. In a fluid pressure brake system, the combination with a train line, a brake valve adapted, in running service position, to feed fluid to the train line, a pressure chamber governed feed valve controlling feed of fluid to the brake valve in such position, a main reservoir, and a second pressure chamber governed feed valve controlling feed of fluid from the main reservoir to the first feed valve, of a double heading valve capable of controlling one of the feed valves and including a valve proper, a pressure chamber, and a piston dividing the pressure chamber and controlling the valve, being subjected, upon one side, to actual train line pressure at all times and normally subjected, upon its other side, to standard train line pressure, and a double heading reservoir at all times communicating with said latter side of the piston.

38. In a fluid pressure brake system, the combination with a train line, a brake valve adapted, in running service position, to feed fluid to the train line, a pressure chamber governed feed valve controlling feed of fluid to the brake valve in such position, a main reservoir, and a second pressure chamber governed feed valve controlling feed of fluid from the main reservoir to the first feed valve, of a double heading valve capable of controlling the first feed valve and including a valve proper, a pressure chamber, and a piston dividing the pressure chamber and controlling the valve, being subjected, upon one side, to actual train line pressure at all times and normally subjected, upon its other side, to standard train line pressure, a double heading reservoir at all times communicating with said latter side of the piston, and means operable upon movement of the double heading valve in one direction, due to venting of the train line for causing a corresponding venting of the double heading reservoir to the atmosphere.

39. In a fluid pressure brake system, the combination with a train line, a brake valve adapted, in running service position, to feed fluid to the train line, a pressure chamber governed feed valve controlling feed of fluid to the brake valve in such position, a main reservoir, and a second pressure chamber governed feed valve controlling feed of fluid from the main reservoir to the first feed valve, of a double heading valve capable of controlling the first feed valve and including a valve proper, a pressure chamber, and a piston dividing the pressure chamber and controlling the valve, being subjected, upon one side, to actual train line pressure at all

times and normally subjected, upon its other side, to standard train line pressure, a double heading reservoir at all times communicating with said latter side of the piston, means operable upon movement of the double heading valve in one direction, due to venting of the train line for causing a corresponding venting of the double heading reservoir to the atmosphere, and means operable upon 5 stopping the venting of the train line for cutting off venting of the double heading reservoir to the atmosphere.

40. In a fluid pressure brake system, the combination with a train line, a brake valve adapted, in running service position, to feed fluid to the train line, a pressure chamber governed feed valve controlling feed of fluid to the brake valve in such position, a main reservoir, and a second pressure chamber 15 governed feed valve controlling feed of fluid from the main reservoir to the first feed valve, of a valve casing, a slide valve mounted in the casing, a piston mounted in the casing controlling the movement of the slide 20 valve, a graduating valve carried by the piston and coöperating with the slide valve, means whereby movement of the slide valve and piston, in one direction, will establish and maintain or if established will maintain 25 communication between the pressure chamber of the first feed valve and train line and will establish communication between one side of the piston and the atmosphere, means whereby slight movement of 30 the piston and graduating valve, in the opposite direction, will cut off such latter communication to the atmosphere, and means whereby movement of the slide valve and piston, in the opposite direction, will establish 35 communication between the main reservoir and pressure chamber of the first feed valve and between the main reservoir and one side of the piston.

41. In a fluid pressure brake system, the combination with a train line, a brake valve adapted, in running service position, to feed fluid to the train line, a pressure chamber governed feed valve controlling feed of fluid to the brake valve in such position, a main 45 reservoir, and a second pressure chamber governed feed valve controlling feed of fluid from the main reservoir to the first feed valve, of a valve casing, a slide valve mounted in the casing, a piston mounted in the casing 50 controlling the movement of the slide valve, a graduating valve carried by the piston and coöperating with the slide valve, means whereby movement of the slide valve and piston, in one direction, will establish 55 and maintain or if established will maintain communication between the pressure chamber of the first feed valve and train line and will establish communication between one side of the piston and the atmosphere, means whereby slight movement of 60

the piston and graduating valve, in the opposite direction, will cut off such latter communication to the atmosphere, and means whereby movement of the slide valve and piston, in the opposite direction, will establish 65 communication between the main reservoir and pressure chamber of the first feed valve and between the main reservoir and one side of the piston, the opposite side of the piston at all times being subjected to the actual train line pressure at such times.

42. A double heading valve including a casing having aligned communicating slide valve and piston chambers, a slide valve seat in its chamber, a slide valve reciprocally mounted upon its seat and having its upper face channeled to provide upstanding longitudinal walls, a piston reciprocally mounted in its chamber and having a stem seating between the walls of the slide valve with its upper face below the upper edges thereof, shoulders formed upon the stem to engage opposite ends of the slide valve, the shoulders being spaced a distance greater than the length of the slide valve, and means for holding the slide valve to its seat, said means including a pressure carriage, a roller journaled in the carriage and formed to simultaneously engage the upper edges of the walls of the slide valve and the piston stem, and means for exerting pressure against the carriage.

43. A double heading valve including a casing having aligned communicating slide valve and piston chambers, a slide valve seat in its chamber, a slide valve reciprocally mounted upon its seat and having its upper face channeled to provide upstanding longitudinal walls, a piston reciprocally mounted in its chamber and having a stem seating between the walls of the slide valve with its upper face below the upper edges thereof, shoulders formed upon the stem to engage opposite ends of the slide valve, the shoulders being spaced a distance greater than the length of the slide valve, and means for holding the slide valve to its seat, said means including a pressure carriage, a roller journaled in the carriage and formed to simultaneously engage the upper edges of the walls of the slide valve and the piston stem, a spring pressing against the carriage, and means for adjustably tensioning the spring.

44. A double heading valve including a valve casing formed with a piston chamber and valve chamber, a piston mounted in the piston chamber and having a stem projecting through the valve chamber, a slide valve seat in the valve chamber, a slide valve operable by the piston stem engaging the seat, a graduating valve carried by the slide valve and also operable by the piston stem, the casing being formed with a port communicating with the piston chamber at one side

of the piston and with a port communicating with the valve chamber and so with the piston chamber at the opposite side of the piston, and a shoulder surrounding the end 5 of the valve chamber and engageable by the piston in one extreme limit of its movement to decrease the area of one of its faces subjected to pressure in such position.

45. A double heading valve including a 10 valve casing adapted, at one end, for communicative attachment to a train line and at its other end for communicative attachment to a double heading reservoir, a piston chamber in the casing, a piston in the 15 chamber subjected, upon one side, to the train line pressure and upon the other to the double heading reservoir pressure, a stem for said piston, a slide valve seat formed in the casing, and a slide valve reciprocally mounted upon the seat and operable by 20 movement of the piston, said slide valve seat having a port communicating with the atmosphere, a port adapted to communicate with a train line, a port adapted 25 to communicate with a feed valve and a port adapted to communicate with a main reservoir and the slide valve having a cavity adapted, in certain positions, 30 to establish communication between that port adapted to communicate with the train line and that adapted to communicate with the feed valve, and a second cavity adapted, 35 in a certain position of the slide valve, to establish communication between that port adapted to communicate with the main reservoir and that adapted to communicate with the feed valve, said latter cavity having a feed groove adapted, when in the above 40 named position, to establish communication between the main reservoir and the double heading reservoir, the slide valve also having a passage opening through its side at one end and adapted, at its other end, to communicate with that port communicating 45 with the atmosphere in one position of the slide valve, and a graduating valve carried by the piston and adapted to open and close said latter passage of the slide valve.

46. In fluid pressure brake systems, the 50 combination with a plurality of locomotive equipments each including a main reservoir, a brake valve and feed valves, and a train line common to all equipments, of means controlling one of the feed valves 55 whereby the feed valves of any brake valve in running service position will upon movement of another brake valve to release position, feed fluid to the train line at a rate solely dependent upon the relative pressures in the main reservoir and train line 60 and the capacity of the passages forming the communication between them.

47. In fluid pressure brake systems, the 65 combination with a plurality of locomotive equipments each including a main reservoir,

a brake valve and feed valves, and a train line common to all equipments, of means controlling one of the feed valves whereby the feed valves of any brake valve in running service position will upon movement 70 of another brake valve to release position, feed fluid to the train line at a rate solely dependent upon the relative pressures in the main reservoir and train line and the capacity of the passages forming the communication 75 between them, and cut off such feed when the train line has been charged to normal pressure.

48. In fluid pressure brake systems, the combination with a train line and a plurality 80 of locomotive equipments each coöperating with the train line and each including a main reservoir, a brake valve and feed valves, of means operable upon one locomotive equipment to give another locomotive 85 equipment control of the former's feed valves, main reservoir and brake valve, said means controlling one of the feed valves of the subservient equipment and permitting such equipment to charge the train line at a 90 rate solely dependent upon the relative pressures in the main reservoir and train line and the capacity of the passages forming the communication between them when the brake valve of the controlling equipment is 95 turned to release position.

49. In fluid pressure brake systems, the combination with a train line and a plurality 100 of locomotive equipments each coöperating with the train line and each including a main reservoir, a brake valve and feed valves, of means operable upon one locomotive equipment to give another locomotive equipment control of the former's feed valves, main reservoir and brake valve, said 105 means controlling one of the feed valves of the subservient equipment and permitting such equipment to charge the train line at a rate solely dependent upon the relative pressures in the main reservoir and train 110 line and the capacity of the passages forming the communication between them when the brake valve of the controlling equipment is turned to release position and preventing the subservient equipment from feeding air 115 to the train line when the brake valve of the controlling equipment is in service position.

50. In fluid pressure brake systems, the combination with a train line and a plurality 120 of locomotive equipments each coöperating with the train line and each including a main reservoir, a brake valve and feed valves, of means operable upon one locomotive equipment to give another locomotive equipment control of the former's feed valves, main reservoir and brake valve, said 125 means controlling one of the feed valves of the subservient equipment and permitting such equipment to charge the train line at a rate solely dependent upon the relative 130 pressures in the main reservoir and train line and the capacity of the passages forming the communication between them.

pressures in the main reservoir and train line and the capacity of the passages forming the communication between them when the brake valve of the controlling equipment is turned to release position and preventing the subservient equipment from feeding air to the train line when the brake valve of the controlling equipment is in service position, the said means being also such that the feeding of air is automatically stopped when the train line pressure becomes normal.

5 51. In fluid pressure brake systems, the combination with a train line, a brake valve adapted in running service position to feed fluid to the train line, a feed valve having a pressure chamber controlling feed of fluid to the brake valve, a main reservoir, a second feed valve having a pressure chamber communicating with the train line and controlling feed of fluid from the main reservoir to the first feed valve, of a double heading valve controlled by train line pressure and when cut in controlling the first feed valve.

10 52. In fluid pressure brake systems, the combination with a train line, a brake valve adapted in running service position to feed fluid to the train line, a feed valve having a pressure chamber controlling feed of fluid

to the brake valve, a main reservoir, a second feed valve having a pressure chamber communicating with the train line and controlling feed of fluid from the main reservoir to the first feed valve, of a double heading valve controlled by train line pressure 35 and when cut in controlling the first feed valve, and manually operable means for rendering the double heading valve active and inactive.

15 53. In a fluid pressure brake system, the combination with a train line, a brake valve adapted in running service position to feed fluid to the train line, a pressure chamber governed feed valve controlling feed of fluid to the brake valve in such position, a main 40 reservoir, and a second pressure chamber governed feed valve controlling feed of fluid from the main reservoir to the first feed valve, of a double heading valve capable of controlling the first feed valve and including a valve proper, a pressure chamber, and a piston dividing the pressure chamber and controlling the valve, being subjected upon one side, to actual train line pressure at all 45 times and normally subjected, upon its other side, to standard train line pressure.

20 In testimony whereof I affix my signature.
WILLIS C. WEBSTER. [L. S.]
